Patented July 18, 1916.

FIG. 1

FIG. 2.

Inventor:
Frank Warner

By Edson Bros.

Attorneys.

UNITED STATES PATENT OFFICE.

FRANK WARNER, OF LONDON, ENGLAND.

FIGURED VELVET FABRIC.

1,191,487.

Specification of Letters Patent. Patented July 18, 1916.

Application filed May 19, 1915. Serial No. 29,175.

To all whom it may concern:

Be it known that I, FRANK WARNER, a subject of the King of Great Britain, residing at 3/4, Newgate street, in the city 5 and county of London, England, have invented certain new and useful Improvements in or Relating to Figured Velvet Fabrics, of which the following is a specification.

10 This invention relates to the manufacture of pile or plush fabrics in which the loops constituting the pile are of different lengths, and particularly of the kind known as velvet with either loop or cut pile or a combination of loop and cut pile, the chief object being to produce figured velvets with varying depths or lengths of pile, whereby richer effects may be obtained than heretofore especially in floral or like designs.

20 According to the invention the design or pattern is produced by looping the pile warp to form different heights of pile, while the bed or ground of the design is formed by looping the warp to effect a short or low pile; thus the various portions of say any 25 floral design may be woven with two heights of pile or plush and a third or higher portion standing out to show effectively above the other and lower or shorter plush.

30 In order that the invention may be clearly understood and readily carried into effect the same will now be more fully described by the aid of the accompanying drawing, in which:—

35 Figure 1 shows by way of example the shading effect produced in the finished fabric; Fig. 2 is a section of a portion of the fabric disclosing the weave and also showing the pile wires opposite their respective piles.

40 *a* indicates the ground warp, *b* the low pile, *c* the mid pile and *d* the high pile while the pile wires *b'*, *c'*, *d'* are shown at the left hand side of Fig. 2; the thickness or depths 45 of the three wires corresponding to the respective piles *b*, *c* and *d*. This method of weave results in the production of three-figure effects superimposed upon each other, thus enabling a facial effect to be obtained 50 in which the high pile constitutes the prominent portion of the figure being woven (see Fig. 1).

The design or pattern to be produced is effected by the jacquard in which the harness is mounted and adapted to operate to 55 give the required lift to the pile warp and thereby enable the wires *b'*, *c'*, *d'*, to be inserted to produce the varying heights according to the pattern or design required to be woven. For example, the high portion of the figure is constituted by the pile warps lifted during the insertion of the highest or deepest wire and the lower parts of the figure are effected by the pile warps lifted at the time of insertion of the medium 60 wires, while the ground is formed by raising the pile warps when the lowest wires are inserted. Certain or all of the pile warps may be left in loop form as may be desired in which case the wires are simply 65 withdrawn to leave the loops intact. In the production of cut pile however the wires may be cut out either by passing a sharp knife along the groove indicated in the upper surface of each wire, or by means of 70 knives or blades attached to the ends of the wires which on being drawn out cause the knives to effect the necessary cutting or severing of the loops as will be well understood.

75 The interweaving of the ground warp, pile warp and weft threads are clearly indicated in Fig. 2 and it will be apparent to those skilled in the art of plush weaving how the various sheds will require to be operated for the purpose of giving the third pile effect referred to.

80 What I claim and desire to secure by Letters Patent of the United States is:—

1. The manufacture of a figured velvet 85 fabric which consists in arranging the pile of loops of selected threads at varying heights in successive wire picks, certain of said loops serving to produce a superimposed figure effect and the remaining loops forming a ground for the pattern.

2. The manufacture of a figured velvet 95 fabric which consists in producing the figure by looping certain selected threads of the pile warp over varying heights of wires 100

adapted to permit of a floral design being woven with two heights of pile and a ground woven with a third and shorter pile from other selected threads lifted by a wire of less 5 depth than the figuring wires.

3. A figured warp velvet fabric in which the pattern is effected by interweaving the

ground warp, the pile warp, and the weft threads to produce pile of varying heights by selecting the threads and inserting high, 10 medium and low wires whereby a third pile effect is obtained which shows effectively above the lower pile.

FRANK WARNER.
